A. S. DEEM,
FUSE PLUG,
APPLICATION FILED JUNE 6, 1919.

Patented Apr. 27, 1920.

Arthur S. Deem, Inventor

By Attorney

UNITED STATES PATENT OFFICE.

ARTHUR S. DEEM, OF READING, PENNSYLVANIA, ASSIGNOR OF ONE-HALF TO CHARLES A. BROSSMAN, OF READING, PENNSYLVANIA.

FUSE-PLUG.

1,338,426.

Specification of Letters Patent. Patented Apr. 27, 1920.

Application filed June 6, 1919. Serial No. 302,207.

To all whom it may concern:

Be it known that I, ARTHUR S. DEEM, a citizen of the United States, residing at Reading, in the county of Berks and State of Pennsylvania, have invented certain new and useful Improvements in Fuse-Plugs, of which the following is a specification.

This invention relates to improvements in fuse plugs, such as are commonly used in electrical circuits.

In the plugs now generally in use, a short piece of fuse wire is located, and when this is fused, the plug has become useless and must be discarded and replaced by a new plug.

It is my intention in the present invention to save the plugs, and to so construct them that the renewal of the fuse wire may be easily and rapidly accomplished, thus utilizing the plug indefinitely, and by the mere insertion of a new section of fuse wire, saving the cost of a new plug in very many instances where heretofore they have been discarded and new plugs used to replace them.

My invention consists of a plug formed with a fuse wire opening through the body of the plug, a screw cap to hold the fuse wire and secure the contact at one end and a screw to hold the fuse wire at the other end, which screw also forms the electrical contact point.

The invention is more fully described in the following specification and clearly illustrated in the accompanying drawing, in which:—

Figure 1 is a central, vertical sectional view of my complete plug.

Fig. 2 is a view showing the inner end of the plug, with the fuse wire held in position by the screw.

Fig. 3 is a detail view, showing the fuse wire with the disk attached to one end thereof.

In the drawing, the numeral 1 designates the outer casing or jacket of the plug, formed to screw into the object on which it is to be used, and 2 is the body portion, which is made of porcelain, as usual.

The numeral 4 designates a longitudinal opening through the length of the plug

body, and in this opening I place a fuse wire 5.

This fuse is formed with a disk 6, attached to one end of the wire, and which disk rests upon the upper surface of the body.

The jacket or casing 2 is formed with an upwardly extending, internally screw-threaded projection 8, and into this projection I insert a screw cap 9, which, when the cap is drawn tight, seats upon the disk 6.

The opposite end of the fuse projects beyond the lower extremity of the body portion to permit its being engaged and held in position by a screw 10, adapted to enter a tapped opening in the body portion 1.

The opening 4 in the plug is made of an exact size or diameter, so that it will receive a fuse no larger than the capacity of the plug, in amperes, which is usually marked on the plug. In this manner, much time will be saved in trying to determine what fuse is required, as the opening will accommodate the proper fuse without question.

It is evident from the above description, that, when the fuse wire is destroyed, it will be necessary only to remove the cap, withdraw the remains of the destroyed fuse, replace it by another, secure the end by the screw 10 and replace the cap.

The many advantages that will accrue from a device of this character are well realized by those versed in the art, and the more important of these is the great saving.

Having thus fully described my invention, I claim:

In a fuse plug, the combination with a body having an opening therethrough, a casing inclosing the body, said casing having an internally screw-threaded upper portion, a fuse located within the said opening, said fuse having an integral disk adapted to be engaged by a screw at one end, a cap adapted to screw into the upper portion of the casing and to engage and secure the said disk.

In testimony whereof I affix my signature.

ARTHUR S. DEEM.
